UNITED STATES PATENT OFFICE.

STANLEY E. BOYNTON, OF OAK PARK, ILLINOIS, ASSIGNOR TO CHARLES E. REED, OF McHENRY TOWNSHIP, ILLINOIS.

LATHE.

Application filed July 7, 1923. Serial No. 650,170.

My invention relates, more particularly, to copying lathes, which operate automatically to form an object, as, for example, a wood blank, into the same shape as a pre-formed pattern, though my invention is not limited, as to certain phases thereof, to so-called copying lathes.

My primary object is to provide in a copying lathe involving the use of both roughing and finishing cutters, for the adjustment of the roughing cutters into different positions as the character of work to be produced varies, in order that the roughing cutters shall operate to produce the maximum roughing cut, and leave for removal by the operation of the finishing cutters, the minimum amount of material; and to provide a novel, simple, inexpensive, and positively operating mechanism for this purpose.

Referring to the accompanying drawings:—

Figure 1 is a plan sectional view of a copying lathe for producing lasts in conformance with a pattern, with the lasts graded in size as desired, the same being equipped with my improvements. Figure 2 is an enlarged sectional view taken at the line 2—2 on Fig. 1 and viewed in the direction of the arrow. Figure 3 is a plan sectional view taken at the line 3—3 on Fig. 2 and viewed in the direction of the arrows; and Figure 4, a fragmentary sectional view of the finishing cutters taken at the line 4—4 on Fig. 3 and viewed in the direction of the arrows.

The particular construction of machine which as to its general features of construction is well known in the art comprises a frame 25 provided adjacent its rear side with a guideway 26 extending longitudinally thereof, and adjacent its front side with upwardly-extending parallel guideways 27 and 28 arranged in overlapping relation as shown. Mounted on the guideways 26 and 27 is a slide 31 which carries the cutting mechanism hereinafter described, this slide being adapted for movement lengthwise of the machine; and mounted on the guideways 26 and 28 is a slide 32 likewise movable in a direction lengthwise of the machine, this slide being provided with guides extending crosswise of the machine on which a slide 33 is mounted to be movable longitudinally thereon, this last-referred-to slide carrying the pattern follower represented at 190.

As the mechanism for rotatably support-

ing the pattern and work to cooperate, respectively, with the follower 190 and the cutting mechanism referred to and mounted on the slide 31, is of well-known construction and the manner of cooperation between the follower and cutting mechanism and the pattern and the work is also well known, and furthermore, as this does not constitute any part of my invention, illustration and description thereof appears to be unnecessary and is, therefore, omitted.

The cutting mechanism of the machine hereinbefore referred to and mounted on the slide 31, comprises, generally stated, (Fig. 1), a so-called roughing cutter represented at 172 and a finishing cutter, represented generally at 173. The roughing cutter 172 in accordance with roughing cutters as commonly provided in this general type of machine, comprises a series of flatwise-disposed cutter elements 174 of successively increasing diameter, with the teeth of adjacent elements staggered, as shown in Fig. 2, these elements being rigidly mounted on a shaft 175 journalled in a gear case 176 rotatably supported on a drive shaft 177 shown as the armature shaft of a motor 178 rigidly secured to the slide 31, the shaft 177 carrying a gear 178 which meshes at all times with a gear 180 on the shaft 175. The finishing cutter 173 comprises a pair of hollow cutters 181 pivotally supported at 182 on oppositely extending ears 183 provided on the outer end of a shaft 184 journalled in a housing comprising uprights 185 provided on the slide 31 between which the gear case 176 is located, the shaft 184 extending through arc-shaped slots 186 in the gear case 176 and carrying a gear 187 which meshes at all times with the gear 179, it being understood from the foregoing that the gear connection between the drive shaft 177 and the shafts 175 and 184 operate to drive these shafts simultaneously in the same direction, the gear 187 by preference being of smaller diameter than the gear 180 whereby the shaft 184 is driven at a greater speed than the shaft 175.

The gear case 176 and shaft 175 are adjustable in the different positions of the shaft 177 to vary the positions of the roughing and finishing cutters relative to the work, to regulate the depth of the cut produced by the roughing cutters, the case 176 being provided with a lug 176^a carrying a

cross shaft 176^b extending at its ends in arc-shaped slots 185^a in the uprights 185 and provided with nuts (not shown) bearing against the outer faces of the uprights 185 5 for holding the gear case 176 in adjusted position.

The hollow cutters 181 are each of the same construction, but face in opposite directions, each being of general cup shape 10 with its open end portion of cylindrical form as represented, the inner surfaces of these portions at the outer edges being chamfered as represented to form circular cutting edges.

In order that the desired clearance between the cutters and the blank be presented, the axes of the shafts 175 and 184 are so disposed as to extend at an angle to the axis of rotation of the pattern and blank, as shown in Fig. 1, the angle therein 15 shown being approximately 26°; and the axes of the cutters 181 are disposed at an angle oblique to the axis of the shaft 184 as shown in Fig. 4.

In the operation of the machine the following 20 lower 190 and the cutting mechanism described are caused to move to the left in Fig. 1 in engagement with the last and blank, respectively, thereby to produce a last in conformance with the pattern.

The arrangement of the roughing and finishing cutters and their adaptability for bodily adjustment about the shaft 177 as an axis, is desirable as thereby the roughing

cutters may be adjusted into different positions, as the character of work to be produced varies in order that they shall operate to produce the maximum roughing cut, and leave for removal by the operation of the finishing cutters the minimum amount of material.

What I claim as new, and desire to secure by Letters Patent, is:

A detachable unitary mount for a cutter head for lathes mounted on the lathe tool carriage and comprising a fixed housing, a drive gear mounted therein, spaced bearings therein in fixed relation to the drive gear, a finishing cutter shaft mounted in said spaced bearings, a gear on said shaft in mesh with the drive gear, a member on said housing disposed at right angles to said drive gear and provided with an arcuate slot, a movable roughing cutter gear housing mounted between said spaced bearings provided with an ear having a hole in register with said slot, clamping means extending through said slot and ear, arcuate openings in the side walls of said movable housing through which the finishing cutter shaft extends, a roughing cutter shaft mounted in said movable housing, and a gear on said roughing cutter shaft continually in mesh with the drive gear in all positions of adjustment of said movable housing.

STANLEY E. BOYNTON.
